UNITED STATES PATENT OFFICE.

AMOS B. HOSTETTER, OF LANCASTER, PENNSYLVANIA, ASSIGNOR TO THE SPECIALTY NOVELTY COMPANY, OF SAME PLACE.

DESIGN FOR A GRATER-DISK.

SPECIFICATION forming part of Design No. 27,531, dated August 17, 1897.

Application filed June 21, 1897. Serial No. 641,712. Term of patent 14 years.

To all whom it may concern:

Be it known that I, AMOS B. HOSTETTER, a citizen of the United States, residing at Lancaster, in the county of Lancaster and State 5 of Pennsylvania, have invented and produced a new and original Design for Grater-Disks, of which the following is a specification, reference being had to the accompanying drawings, forming part thereof, in which—

10 Figure 1 is a plan view of the front face of a grater-disk showing my design. Fig. 2 is a similar view of the rear face of the disk, and Fig. 3 is a sectional view on the line $x-x$ of Fig. 1, these three views being deemed 15 necessary in order to fully illustrate my design.

Referring to the drawings, the leading or material feature of my design consists of a series of radially-disposed slits or openings 20 A, one edge of which is ornamented by a series of teeth or notches B, disposed and arranged as illustrated in Figs. 1 and 2. These slits or openings A when viewed from the front face of the disk and in section are countersunk or beveled, as at a , along all the sides 25 or edges, and that edge next or nearest the center of the disk is rounded, as at a' ; but when viewed from the rear face of the disk and in section these slits A are flat and substantially 30 rectangular in shape, the edge nearest

the center of the disk being curved. The teeth or notches B are arranged along one edge of the slits A on the rear face of the disk and project at an angle to and away from the rear face, being arranged in a plane which is 35 substantially a continuation of the beveled edge a of the slit. The teeth B of one slit are not arranged concentrically with the teeth B of the next slit, but are arranged in staggered relationship thereto—that is, an indentation is followed in the next slit by a tooth, and vice versa. 40

The disk may be circular, or substantially so, in outline, and on each face at or about the center or hub is formed a circular ornament 45 b , as clearly illustrated in Fig. 1 of the drawings.

Having thus described the nature of my invention, what I claim as new, and desire to secure by Letters Patent, is—

50 The design for a grater-disk, comprising the front and rear faces of the disk, substantially as shown and described.

In testimony whereof I have hereunto set my signature in the presence of two subscribing witnesses.

55 AMOS B. HOSTETTER.
